UNITED STATES PATENT OFFICE.

JAMES L. BALDWIN, OF CHICAGO, ILLINOIS.

TRAVELING AND ELEVATING PARCEL-CARRIER.

1,270,099.

Specification of Letters Patent. Patented June 18, 1918.

Application filed August 13, 1912. Serial No. 714,911.

To all whom it may concern:

Be it known that I, JAMES L. BALDWIN, a citizen of the United States, residing at Chicago, in the county of Cook and State 5 of Illinois, have invented a new and useful Traveling and Elevating Parcel-Carrier, of which the following is a specification.

My invention relates to wire line carriers and more especially to what I have termed 10 up-thrust and down-chute carrier apparatus and the objects of my improvements are, first to afford provisions in wire line service whereby a carrier may rise over obstructions such as partitions, grilles, etc., or 15 may rise to an upper floor and run at right angles to a station located at a considerable distance from the lower sending point; second, to provide a continuous track partly horizontal and partly vertical and a car to partly 20 travel on said track; third, to connect a horizontal track and a vertical with a curved track and provide an elevator or carriage in connection with the vertical track; fourth to provide a vertical track with an elevator or 25 carriage which will automatically be released to elevate or lower a car by the presence of the car; fifth, to make a neat, efficient and durable device, and other features to become apparent from the description to follow.

In store service apparatus for transmitting parcels from place to place, it is often required that the car containing the parcel be made to travel up an incline, as for instance 35 when passing from a counter on the floor to a station located on a balcony or other elevation. Heretofore such transmission has been accomplished by the use of an inclined track and a car to travel on said 40 track. It is necessary in such devices to exert a considerable amount of propelling force to make the car reach the elevated station and time and patience are often consumed by the car failing to be thrown with 45 sufficient force to reach the elevated station and, of course, the operation has to be repeated. By the use of my invention all inclines of the track of any perceptible degree are eliminated and only a slight degree 50 of propelling force is required to send the car from a low station to an elevated station. My invention comprises a track in substantially a horizontal plane with a vertical portion at the end of same, and an 55 elevator or carriage is provided in connection with the vertical portion to automatically

raise or lower the car upon its arrival at the vertical portion of the track.

To describe my invention so that others versed in the art to which it pertains can 60 make and use the same, I have illustrated it on the accompanying two sheets of drawings forming a part of this specification, in which:—

Figure 1, is a sectional view of a portion 65 of a building showing a device embodying my invention arranged to transmit parcels from one floor to another; Fig. 2, is a perspective view of said device enlarged and foreshortened; Fig. 3, is an enlarged elevation of the upper end elevator or carriage and co-acting parts; Fig. 4, is an elevation of the same viewed at right angles from that shown in Fig. 3, and Fig. 5, is a plan view 70 of the same.

Similar reference characters refer to similar parts throughout the several views.

The two side walls of a building are shown at 6 and a floor supported by the walls at 7. The track is preferably constructed 80 of a single wire 8 and as illustrated is secured to the floor by suitable supports to be held taut in substantially a horizontal position throughout its middle portion and in a vertical position at each end of the 85 horizontal part as shown at 9 and 10, said vertical portions being a continuation of, and connected by means of the curves 11 and 12, to, the middle portion 8. It will be noted that the vertical track 9 is below 90 the horizontal track 8 and that the vertical track 10 is above the horizontal track 8; furthermore, it will be noted especially in Fig. 1, that the end of the horizontal portion 8 nearest the lower vertical track 9 is 95 slightly lower than the other end near the upper vertical track 10. This slight inclination of the horizontal track is made for the purpose of causing the car 13 to normally gravitate along on the track 8 100 from the vertical track 10 to the vertical track 9. Thus the car 13 is prevented from becoming stalled on the horizontal track 8.

When the car 13 travels on the horizontal track 8 the parcel container attached to the 105 car serves to retain the car in an upright position but when the car is traveling along either of the vertical tracks 9 or 10 it is free to turn about the track wire as a pivot into a position to bring the parcel container 110 on any side of said wire and to retain said parcel container on the proper

side of the vertical wire to correspond with the lower side of the horizontal wire 8 after the car passes around the curve. I provide two guide wires 14 parallel to the vertical track wires 9 and 10 in such position that the parcel container on the car will pass freely between said two wires 14, but will be prevented by said two wires from turning about the vertical track wire as a pivot. The ends of the guide wires 14 are secured to suitable fixed brackets provided for the purpose and to be described later.

The curved tracks 11 and 12 are constructed similarly and each comprises a sheet metal strip 15 which is bent to conform with the desired curve of the track and has one edge 16 curled snugly around the curved track wire and its remaining edge 17 rigidly secured as by bolts 18 to a bar 19 also curved to conform to the desired curve of the track. A companion bar 20 is provided to parallel the bar 19 and the two bars are adjustably connected together at suitable intervals as by screws and slotted brackets 21. At that end of the curved track which connects with the vertical track the ends of the rods 19 and 20 are rigidly secured by screws or otherwise to a bracket 22 of semicircular form, best seen in Fig. 5, which is rigidly secured in position by means of a ceiling stay 23 or otherwise. The two extremities of the bracket 22 are equal distances from the track wire and have the ends of the guide wires 14 attached thereto. Thus the bracket 22 serves to hold the bars 19 and 20, the guide wires 14 and the track wire in proper position with relation to one another. At that end of the curved track which connects with the horizontal track the ends of the two rods 19 and 20 are secured to another semicircular bracket 24 which yokes over the track wire; the one extremity of the bracket 24 is rigidly connected to the rods 19 and 20 and the other extremity of said bracket 24 is connected to and supports a short guard rail 25, which is directly opposite to the flaring guard rail 26 formed on the one end of the rod 20. The guard rails 25 and 26 are positioned equal distances from the track wire and at such distance from each other that the parcel container on the car can pass freely between the two.

55 An elevator or carriage for the car 13 is provided in connection with each vertical track so that the car is delivered automatically at the extreme vertical ends of the track. It will of course be apparent that the elevator or carriage at the lower vertical track must automatically carry the car from a high position to a low position while the other elevator or carriage at the upper vertical track must automatically carry the car from a low position to a high position.

The construction and the operation of both elevators or carriages being similar, I will proceed to describe the elevator or carriage provided in connection with the upper vertical track 10 as illustrated in Figs. 3, 70 4 and 5.

The elevator or carriage comprises the rectangular frame 27 provided with perforations through which the guide wires 14 pass, so that the elevator or carriage is free 75 to move up and down on said guide wires 14. A suitable cord 28 is attached to the elevator or carriage at 29 and extends upward and over a suitable idler and has a weight 28' attached to its ends of sufficient 80 heft to lift the elevator or carriage and car 13 together with the contents of the parcel container. A spring pressed latch 30 pivoted to a suitable extension on bracket 22 is provided to automatically catch over a 85 suitable extension on the elevator or carriage and prevent said elevator or carriage moving upward until the said latch is withdrawn by the presence of the car 13, which will engage the lower free end of the latch 90 30 which is normally held in the path of the car. The end of the car 13 is provided with a perforation 31' into which the spring pressed catch 31 automatically latches when the car 13 comes into contact with the elevator or carriage. The catch 31 is pivotally mounted on the elevator or carriage in proper position to register with the co-operating perforation on the car 13.

In operation the car 13 is given a slight 100 push or thrust by operating the elevator or carriage on the lower vertical track 9 to be described; the car travels along on the horizontal track 8 and its momentum will carry the car upward around the curved track 12 105 and against the lower end of the elevator or carriage which is being retained in its lower position by the latch 30. As the car 13 thus contacts with the elevator or carriage it is locked to the elevator or carriage 110 by the catch 31 as above described, and the latch 30 is withdrawn from engagement with the elevator or carriage by the car as above described, and the elevator or carriage with the car attached thereto is lifted 115 by the weight as above described into a position at the upper station at the top end of the vertical track 10. To return the car from the upper station to the lower station the elevator or carriage 27 is pulled down 120 by manual force by pulling upward on the cord 32 which passes around the idler 33 pivotally mounted on some part of the bracket 22 and thence passes upward and has its end secured to the elevator or carriage 27 at 29. For convenience the cord 28 and the cord 32 may be integral and secured to elevator 27 at 29. Thus the elevator or carriage is pulled down against the exertion of the weight fastened to the end 130

of the cord 28, until it comes to a stop with its spring bumpers 34 against the extremities of the semicircular bracket 22. Just before the elevator reaches its lowermost position as mentioned, the tail end 35 of the catch 31 has contacted with the extension 36 of bracket 22 and disengaged the catch 31 from car 13, so that the car will fall by force of gravity away from the elevator or carriage 27 and downward around the curved track 12 and thence along the horizontal track 8 and thence downward around the curved track 11 and onto the elevator or carriage 37 on the lower vertical track 9. It will be noted that the position of the elevator or carriage on vertical track 10, when being held by latch 30, is some distance above its lowermost position; this is thusly arranged so that the car 13 when leaving the elevator or carriage 27 in its downward course will be past the point where it engages the tail end of the latch 30 and the said latch is in position to retain the elevator or carriage in its lower position as soon as the pull on the cord 32 is released.

The lower elevator or carriage 37 is constructed similar to the upper elevator or carriage 27 and arranged to slide up and down on the guide wires 38, stretched taut between the bracket 22 of the curved track 11 and a suitable station bracket 39 secured to a desk or counter. Both elevators or carriages are preferably provided with spring bumpers 34 at one end to engage the bracket 22 of the curved track, and with spring bumpers 40 at the other end to engage with the station bracket and also with a spring bumper 41 to receive the impact of the car 13. The lower elevator or carriage 37 does not require a catch 31 for the car because the car will by force of gravity follow the elevator or carriage 37 downward; neither is it necessary to provide a latch 30 to retain the elevator or carriage 37 in position nearest to the curved track 11 because I provide a weight 42 to normally hold the elevator or carriage 37 in its uppermost position. The weight 42 is attached to one end of a cord 43 which passes up around an idler 44 and thence down to and is attached to, the elevator or carriage 37. The weight 42 is only slightly heavier than the elevator or carriage 37 and is lighter than the combined weight of the elevator or carriage 37 and car 13, so that the elevator or carriage alone will always be held in its uppermost position but when the car 13 rests on the elevator or carriage it will move down into its lowermost position against the upward pull caused by the weight 42.

In operation the car 13 after leaving the upper station and the elevator or carriage 27 travels along on the horizontal track 8, thence around on the curved track 11 and thence down onto the elevator or carriage

37 and finally down with the elevator or carriage to the lowermost position against the station bracket 39. To send or throw the car 13 up and out from the lower station the elevator or carriage is raised by 70 manual force until it comes to a stop with the bumpers 34 against the bracket 22 of the curved track 11. The elevator or carriage 37 is raised with sufficient force to give the car 13 a sufficient thrust and momentum to pass up around on the curved track 11, travel the entire length of the track 8 which is slightly inclined as above noted and finally to travel up around on the curved track 12 into contact with elevator or carriage 27. To conveniently raise the elevator or carriage 37 as required I attach one end of a pull cord 44' to the elevator or carriage 37, pass the said cord upward over a multiple of pulleys and secure the other end to a pulley block 45, to which I secure a handle 46 to be grasped by the hand of the operator.

It will be understood that numerous changes may be made in the construction 90 of the parts as shown and described without in the least departing from the scope of the invention.

Having thus fully described my invention what I claim as new and desire to secure by 95 Letters Patent of the United States is:—

1. A track comprising a horizontal section with a vertical section at one end below the horizontal section and a vertical section at the other end above the horizontal section, a car to travel on said track, a combined catcher and thrower for the car guided to travel parallel to the lower vertical section of the track comprising a suitable frame with buffer springs and a pull cord and counter weight to operate said combined catcher and thrower, a combined catcher and elevator for the car guided to travel parallel to the upper vertical section or the track comprising a suitable frame 100 with buffer springs and a pull cord for operating said combined catcher and elevator. 105

2. In a device of the class described, a track comprising a horizontal section with a vertical section at one end below the plane 115 of the horizontal section, a car to travel on said track, a combined catcher and thrower for the car guided to travel parallel to said vertical section comprising a suitable frame with buffer springs at each end, means for yieldingly holding said combined catcher and thrower in an elevated position in the absence of the car and a pull cord for operating said combined catcher and thrower. 120

3. In a device of the class described, a track comprising a horizontal section with a vertical section at one end above the plane of the horizontal section, a car to travel on said track, an elevator for the car guided to move parallel to said vertical 125 130

section comprising a suitable frame with buffer springs at each end, means for locking the elevator in its lower position in the absence of the car and a pull cord for operating said elevator.

- 5 4. In a device of the class described, a track comprising a horizontal section with a vertical section at one end below the horizontal section and a vertical section at the 10 other end above the horizontal section, a car to travel on said track, a combined catcher and thrower for the car guided to travel parallel to the lower vertical section of the track, a combined elevator and catcher for 15 the car guided to travel parallel to the upper vertical section of the track and suitable pull cords to operate said combined catcher and thrower and said combined elevator and catcher.
- 20 5. In a device of the class described, a track comprising a horizontal section with a vertical section at one end below the horizontal section, a car to travel on said track, vertical guides adjacent said vertical section of the track, a combined catcher and thrower for the car mounted to travel on 25 said guides, buffer springs on the lower end of said combined catcher and thrower and buffer springs on the upper end of said combined catcher and thrower.

30 6. In a device of the class described, a track comprising a horizontal section with a vertical section at one end above the horizontal section, a car to travel on said track, a combined catcher and elevator for the car guided to move parallel to said vertical section and counterweighted to normally rest in its upper position and a pull cord for lowering said combined catcher and elevator.

35 7. In a store service apparatus, the combination with substantially vertical and substantially horizontal ways for guiding a car upwardly and laterally to a station at a higher level, said ways being connected by an intervening track curve, an elevator in parallel relation to said upward way for supporting a car, a car adapted to travel on said ways and curve, propelling means for 40 lifting said elevator and yielding counterpoise means adapted to hold said elevator in a raised position when the car is removed therefrom, while free to yield to the combined weight of the elevator and car to permit the descent of the latter.

45 8. A store service apparatus, comprising an elevator, means for guiding the same up and down, cord propelling means for lifting said elevator, a wheeled car adapted to be supported by said elevator during its upward and downward movement, a track way in parallel relation to the path of said elevator for engaging the wheels of said car, a lateral way at a level above the topmost 50 height to which said elevator is adapted to

be moved, a track curve for connecting said lateral with said up and down ways and yielding means for holding said elevator in a raised position when the car is not resting thereon but adapted to yield to the weight 55 of the elevator and car together.

9. In a store service apparatus, the combination with substantially vertical and substantially horizontal ways united by a curved connection, of an elevator in parallel relation to said upward way for supporting a car thereon, the wheels of which car are arranged to successively engage said ways during its travel, a car adapted to be supported by said elevator when its wheels are 60 in contact with said vertical way, counterpoise means for holding said elevator at its topmost level when the car is not resting thereon, but adapted to permit its descent when weighted by the car, propelling means for causing the ascent of said elevator and car and propelling means for returning said car upon said horizontal way whereby it may be caused to fall upon said elevator and cause the descent of the latter.

65 10. In a store service apparatus, the combination with upward and substantially horizontal ways united by a curved connection to form communication between upper and lower stations, of an elevator in parallel relation to said upward way for supporting a car thereon, the wheels of which car are arranged to successively engage said ways during its travel, a car adapted to be supported by said elevator when its wheels are in contact with said upward way, counterpoise means for holding said elevator at its topmost level when the car is not resting thereon, but adapted to permit its descent when weighted by the car, propelling means at 70 said lower station for lifting said elevator and propelling means at said upward station for returning said car to said elevator.

75 11. In a store service apparatus, the combination of an upward way leading from a station on a given floor, a substantially horizontal way leading to a station upon a higher floor, a curved track connection for uniting said ways, an elevator in parallel relation to said upward way for supporting a car, the wheels of which are arranged to follow said ways and track connection, a car adapted to be supported by said elevator when its wheels are in contact with said upward way, means for guiding said car around said curved connection to maintain the body thereof in a given plane, counterpoise means for holding said elevator at its topmost level when the car is not resting thereon but adapted to permit its descent when weighted by the car and propelling means located at 80 the respective stations.

85 12. A store service apparatus, comprising in combination upwardly and laterally directed ways united by a connecting portion 85

to form a substantially continuous way from the receiving to the delivery stations, a carrier adapted to travel along and under the constant control of said continuous way, 5 manually operable means for raising the carrier along the upwardly directed portion of said way to the connecting portion to impel it by momentum over said connecting portion and along the laterally directed portion without intermission of track control, 10 means for retaining said raising means at a predetermined height in proximity to said connecting portion when the car is not resting thereon and manually controlled means 15 for causing the return of said car from the delivery station to said raising means.

18. A store service apparatus, comprising in combination, upwardly and laterally directed ways united by means of a curved connection to form a continuous way between lower and upper stations, elevating means 20

for supporting a wheeled car thereon, the wheels of which are arranged to contact continuously in their travel with said continuous way, a car adapted to be supported by 25 said elevator when its wheels are in contact with said upward way, means for maintaining said elevator at a predetermined level when the car is not resting thereon, propelling means at said lower station for lifting 30 said elevator and car, and propelling means at said upper station for returning said car to said elevator.

In testimony whereof I have signed my name to this specification in presence of two 35 subscribing witnesses this 10th day of August 1912 at Chicago, Illinois.

JAMES L. BALDWIN.
